(57) **CLAIM**

I claim the ornamental design for a seafood extraction tool, as shown and described.

DESCRIPTION

FIG. 1 is a perspective left-side upper view of the seafood extraction tool showing our novel design;

FIG. 2 is a perspective right-side lower view thereof;

FIGS. 3 and 4 are front and rear elevation views thereof, respectively;

FIG. 5 is a right-side elevation view thereof, with the left-side elevation view being a mirror image thereof;

FIG. 6 is a top plan view thereof; and,

FIG. 7 is bottom plan view thereof.

The broken lines shown represent unclaimed subject matter and form no part of the claimed design.
